ELECTRICAL RESISTOR AND METHOD OF MAKING SAME

Joseph J. Cerny, Chicago, Ill.

Application June 28, 1948, Serial No. 35,714

12 Claims. (Cl. 201—67)

1

This invention is directed to novel resistors, particularly of the type adapted to be used in a wide variety of devices, electrical apparatuses, and electrical circuits, and appliances, in which a relatively great degree of accuracy is required in the resistors therein used.

It is an important object of my invention to provide a resistor, in which the degree of accuracy is relatively very great, by pre-determining the resistance in the wire to be effectively used. More primarily my invention is directed to a novel method or process of more quickly and economically manufacturing portable resistance units in which the degree of accuracy is very great.

A further object and accomplishment of my invention is the provision of resistors adapted to be connected in electrical circuits, said resistors including an elongated body, metal end caps mounted on the respective ends thereof, terminal circuits wires, and a resistance wire of pre-determined resistance.

A further object and accomplishment of my invention is the provision of a novel method of rapidly manufacturing resistors, for electrical circuits, in which the initial forms of the resistors include a non-conductive core into the ends of which terminal circuit wire having been irremovably set, and which method provides for anchoring a resistance wire at the opposite ends thereof to said terminal circuit wires, connecting said aforesubscribed structures in circuit with an ohmmeter, winding said resistance wire around said terminal wires until a required resistance is registered, and then winding the remaining resistance wire upon said core.

It is a further object and accomplishment of my invention to provide a resistor in which induced magnetic fields do not affect the resistance of said resistor, by uniformly spirally winding one-half of said resistance wire in one direction upon the core, and by spirally winding the other half thereof in an opposite direction so that the magnetic fields set up will equalize each other.

A further object of my invention is to provide a novel core or body in a resistor so that the resistance wires which are wound about said core may be securely anchored so that said resistance wire will not slip off said core.

It is a further object of my invention to provide a novel resistor of great accuracy in which the end caps thereof are of a shape to render said resistors not useless in the event the circuit wires thereof break off, but providing each of said end caps with an integral outwardly extending flange through which said terminal circuit wires

pass. In the event of breaking therefore, of said terminal wire, said breaking will most probably occur adjacent to said outwardly extending flange.

My novel construction and method herein described is adaptable to a large variety of sizes of resistors, and because of the method employed, laboring costs, which are a sizeable portion of the cost of the resistors, of the type herein described, may be substantially reduced.

10 Other and further important objects of my invention will be apparent from the following description and appended claims.

15 One embodiment of my invention is illustrated in the accompanying drawings bearing numbers of reference referred to in the accompanying specification.

On the drawings,

Fig. 1 is a cross sectional view of the core showing the circuit wires embedded.

20 Fig. 2 is a front elevation of my core winding device.

Fig. 3 is an elevational view of the core in the final stage of being wound with resistance wire.

Fig. 4 is an elevational view showing the core and one terminal end cap placed thereon.

Fig. 6 is a completed view of my resistor.

30 Referring to the drawings, reference numeral 10 designates a cylinder, or rounded core, or body, made of a suitable non-conductive material such as a thermo plastic or thermo setting resin. Said body 10 may vary widely in its dimensions de-
35 pendent upon the size of resistor required. As

illustrated in Fig. 1, terminal circuit wires 11 are embedded into the substance of the core or body 10, one of said wires being positioned in one end thereof and the other of said wires being positioned or set into the opposite end thereof. The wires 10 are preferably set into the core during the manufacture thereof, preferably while the substance or material of which said core is made is in a tacky state, before the setting and solidifying thereof. Said terminal wires 11 are preferably centered with respect to their respective ends of said core; and said wires preferably extend outwardly of said core as a continuation of the longitudinal axis thereof. Preferably each of the terminal wire ends or pigtaills 11 is formed in the shape of a J, to provide an anchoring member with the shorter leg 12 of said J-shaped wires extending laterally of the core for a slight distance, said shorter leg 12 being preferably parallel to the longer leg of said wire 11 and preferably

spaced therefrom by substantially the diameter of the wire 11, as illustrated in Figs. 1, 2, and 3.

As illustrated in Fig. 2, numeral 13 represents a vertical board, brace, or support member, or its equivalent, which is preferably made of some non-conductive material, and which is preferably suitably mounted in any appropriate fashion to assure rigidity. A conductive expansion spring or its equivalent 14 is mounted on preferably the upper portion of said support 13, preferably by means of a bracket 20, and a retaining screw and nut designated generally as 21. Preferably two immovable non-conductive pins or members 15 are removably positioned in a substantially horizontal line on the front face of support member 13. Said pins 15 are spaced apart slightly more than the length of the core 10. It is to be understood that the pins 15 may be set in said support to correspond to any variety of core sizes.

As illustrated in Fig. 2, numeral 16 represents a pair of rotatable holding or gripping members, such as chucks or arbors, one of which members grips the unembedded end of one of the wires 11, and the other of which members grips the unembedded end of the other of said wires 11 during the normal winding operation. Gripping members 16 are preferably mechanically rotatable.

With the embedded wires 11 gripped as afore-described the respective ends of resistance wire 17 are anchored on the opposite wires 11 by anchoring or locking said resistance wires in any suitable manner to the leg 12 of the wire 11 and the body of the wire 11. An intermediate portion of the wire 17 is preferably anchored to lowermost portion of the spring 14 so that said wire during the normal operations assumes the shape of an inverted V. The wire 17 is preferably sufficiently short so that, at all times during the process, a tension or pull is created on the spring 14 while the core 10 is held suspended between the chucks 16. By placing the pins 15 in an appropriate position, the opposite end portions 22 of the wire 17 becomes substantially parallel to each other as illustrated in Fig. 2.

As illustrated in Fig. 2 the circuit wires 11 are connected in series to an ohmmeter or any suitable instrument 19 for indicating resistance, by means of appropriate wires designated generally as 18. It is to be understood that I am not limiting myself to the use of an ohmmeter, but that any instrument or group of instruments, or their equivalents for determining resistance, may be used.

By turning the chucks, the anchored ends 22 of the wires 17 are wound around the wires 11 at substantially the positions where said ends are anchored, due to guiding by the pins 15. When the proper length of resistance wire remains unwound on the wires 11, as determined by a reading on the ohmmeter 19, the pins 15 are removed by an operator and further winding on the wires 11 is stopped. An operator then causes the two opposite then unwound end parts 22, of the resistance wire 17, to engage and be gripped in the respective beveled recesses 23, one of which is positioned in each end of the core 10 as illustrated in Fig. 2. This anchoring precludes the slipping off of the resistance wire from the core 10. As the rotation of the core again commences, the remaining length of unwound resistance wire 17 is wound upon said core 10, because of the yielding of the spring 14.

Due to the aforesubscribed procedure of anchoring the wire 17 upon the spring 14, the wire 17

which is wound around the core is disposed in a spiral path on and about the core 10, so that substantially one half of said resistance wire is disposed spirally in a direction opposite to the other one half thereof. The wire 17 is wound on the core until said wire has dissipated itself in winding about said core, with the apex thereof being disposed adjacent to the central portion of said core 10 as illustrated in Fig. 3. Thereupon, said apex is removed from said spring 14, and is caused to be retained by applying a suitable non-conductive adhesive for causing retention of said wire against said core 10. The core and wound resistance wire are then removed from the gripping members 16, are preferably coated and covered with a suitable non-conductive material 23.

As illustrated in Figs. 4, 5, and 6, numeral 24 represents a metal end cap or member which is preferably formed with an outwardly projecting annular flange 25 in the bottom thereof. Said flange 25 defines an opening in the bottom of said cap which is preferably centrally disposed. The opening defined by the flange 25 is of a sufficient size to permit the positioning of the wire 11, leg 12, and the anchored end of the wire 17 therein. The inner diameter of the annular wall 27 of the cap 24 is substantially the same as the diameter of the core and resistance wire assembly with their non-conductive coating.

After the core and resistance wire have been assembled, and preferably after the application of a non-conductive coating thereto, a metal end cap 24 is preferably impinged and securely positioned on each end of said assembly, as illustrated in Fig. 4. To further secure said caps to the wires 11 and the ends of the wire 17 anchored thereon I use an appropriate material such as solder.

By my method, I can produce resistors of relatively high accuracy at a relatively low cost for resistors of that degree of accuracy.

It is to be observed that after determining the exact effective resistance, I preclude the interference of induced magnetic fields, with the measured resistance, by winding the resistance wire in opposite spiral paths on opposite halves of the core bodies, causing the effect of electrically equalizing the two fields thus set up.

I apply a suitable non-conductive coating or covering upon the core bodies with the metal end caps thereon; for example, using material such as porcelain enamel, which, when dried and baked, effectively protects the resistor over its entire length and leaves only the terminal circuit wires 11 projecting therefrom. Such enamel coating has high heat conductivity and quickly dissipates the heat developed in the resistor element.

It is to be understood that during the winding of the resistance wire 17, the ohmmeter 19 may be kept in series with said resistance wire wound and unwound upon the core 10 so that any increase in the resistance of the wire 17, which is to be wound on said core, due to stretching which may occur, after said winding thereupon has begun, may be registered on said ohmmeter 19. If any increase in resistance does occur, said increase may be negated by adding solder to unite appropriate portions of the resistance wire 17, or by any equivalent means.

The present invention has been described herein more or less as to details, yet it is to be understood that the invention is not to be limited thereby, as changes may be made in the arrangement

and proportion of parts, and equivalents may be substituted without departing from the spirit and scope of the invention.

I claim:

1. A resistor for electrical circuits or the like, a core; a resistance wire wound around said core; a terminal circuit wire mounted on each end of said core and projecting outwardly therefrom; and an end portion of one end of each circuit wire bent back and extending outwardly from said core, said end portions being parallel to said circuit wires and spaced slightly therefrom, said end portions cooperating with said circuit wires providing means for anchoring the opposite ends of said resistance wire.

2. In a resistor for electrical circuits and the like, a core; a resistance wire of predetermined resistance wound around said core, said resistance wire being wound in slanting spiral paths upon said core, one half of said spiral resistance wire sloping in one direction and the other half thereof slanting in a direction substantially opposite to said first one half thereof; terminal circuit wires mounted on said core and projecting outwardly therefrom; and end leg on each of said wires bent back on said circuit wires and projecting outwardly from said core, said end legs being parallel to said circuit wires respectively and spaced slightly therefrom, said end legs cooperating with said circuit wires to provide means for anchoring the ends of said resistance wire.

3. In a resistor for electrical circuits and the like, a core; a resistance wire wound around said core, said resistance wire being wound in slanting spiral paths upon said core, one half of said spiral resistance wire sloping in one direction and the other half thereof slanting in a direction substantially opposite to said first one half thereof; terminal circuit wires mounted on said core and projecting outwardly therefrom; a short integral leg of each of said circuit wires being bent and extending outwardly of said core, said legs being parallel to said circuit wires respectively and spaced slightly therefrom, said integral legs cooperating with said circuit wires respectively to provide means for anchoring the ends of said resistance wire; a non-conductive coating covering said core and said resistance wire wound thereupon; and end caps securely mounted on each end of said core over said non-conductive coating, said circuit wires projecting therethrough.

4. In a method of making resistors for electrical circuits and the like, of high accuracy, the steps of first measuring an intermediate portion of a resistance wire to a length to correspond to a given resistance and before same has been wound on a core, then securely anchoring the unmeasured ends of said resistance wire to the terminal circuit wires of said core, and winding said intermediate portion on said core having terminal circuit wires projecting therefrom.

5. In a method of making resistors for electrical circuits and the like, of high accuracy, the steps of first measuring an intermediate portion of a resistance wire to a length to correspond to a given resistance; winding said intermediate portion on a core having terminal circuit wires projecting therefrom, said resistance wire wound on said core being wound in spiral paths so that one-half thereof slants in a direction opposite to the other half thereof; securely anchoring the unmeasured ends of said resistance wire to said terminal circuit wires before winding said resistance wire on said core; covering said core

and said resistance wire with a non-conductive coating; and securely mounting conductive end caps on the ends of said core over said non-conductive coating so that said terminal circuit wires project therethrough, said end caps each having an outwardly projecting annular flange covering a portion of said circuit wires and said ends of said resistance wire anchored thereon adjacent said core, said flange being united to said circuit wires and said anchored ends of said resistance wire.

6. In a method for making resistors for electrical circuits and the like of relatively high accuracy, substantially as recited in claim 4 wherein one half of said resistance wire wound upon said core is wound in spiral paths upon said core, sloping in one direction, and the other half of said resistance wire is wound about said core sloping in a direction substantially opposite to the first one half thereof.

7. In a method for making resistors for electrical circuits and the like, of relatively high accuracy, the steps of anchoring the opposite ends of a resistance wire to the opposite circuit wires of a core body; electrically connecting said anchored resistance wire and said terminal circuit wires with a resistance measuring mechanism; simultaneously winding the ends of said resistance wire upon said circuit wires until a length of resistance wire corresponding to a specific predetermined resistance has been reached, and then winding said measured length of resistance wire corresponding to said given resistance on said core body.

8. In a method for making resistors for electrical circuits and the like, of relatively high accuracy, substantially as recited in claim 7, wherein one-half of said measured resistance wire is wound in spiral paths on one-half of said core body and the other half of said resistance wire is wound in spiral paths in a direction substantially opposite to said first half thereof on the other half of said core body.

9. In a method for making resistors for electrical circuits and the like, of relatively high accuracy, the steps of anchoring an intermediate portion of a resistance wire to a yieldable tension means; anchoring the opposite ends of said resistance wire to the opposite circuit wires of a core body; electrically connecting said anchored resistance wire and said terminal circuit wires with a resistance measuring mechanism; then simultaneously winding said resistance wire ends upon said circuit wires until a length of resistance wire corresponding to a specific pre-determined resistance has been reached; and then spirally winding said measured length of resistance wire corresponding to said given resistance on said core body so that one half of said resistance wire wound upon one half of said core body slopes in a direction opposite to the other half thereof on the other half of said core body.

10. In a method for making resistors for electrical circuits and the like, of a relatively high degree of accuracy, the steps of securely mounting a conductive terminal circuit wire in each end of a core body; rotatably gripping the ends of said circuit wires; connecting a resistance wire at an intermediate point thereon to a yieldable means; holding the depending end portions of said resistance wire parallel to each other; securely anchoring the ends of said parallel depending end portions of said resistance wire to opposite circuit wires of said core body, thereby

developing a tension on said yieldable means; electrically connecting said anchored resistance wire and terminal circuit wires with a resistance measuring mechanism; rotating said core so that the ends of said resistance wire are simultaneously wound on said terminal circuit wires until a length of resistance wire remains unwound corresponding to a predetermined resistance, as indicated by said resistance measuring mechanism; removing the means for holding said ends of said resistance wire parallel to each other so that the remaining resistance wire is in the shape of an inverted V; anchoring the opposite ends of the unwound resistance wire on respective opposite ends of said core body; then rotating said core so that the measured length of said resistance wire is wound in spiral paths upon said core until said yieldable means is drawn adjacent substantially the center of the length of said core body, one half of said measured resistance wire being wound on substantially one half of said core body, and the other one half of said measured resistance wire being wound on the other one half of said core body, said second one half of said measured resistance wire sloping in a direction opposite to the first one half thereof; and then securing said intermediate point of said resistance wire against said core.

11. In a method for making resistors and the like for electrical circuits and the like, winding the ends of a wire on a conductor until a predetermined electrically measured resistance has

been reached in said wire and then winding the remaining portions of said wire on a core body.

12. In combination with a method for making electrical resistors and the like, winding a wire on the terminal ends of a core body until a predetermined electrically measured resistance has been reached in said wire and then winding the remainder of said wire on a core body so that a portion of said remainder slopes in one direction and another portion of said remainder slopes in an opposite direction.
